UNITED STATES PATENT OFFICE

JABEZ WILKINSON, OF FALL RIVER, MASSACHUSETTS

WARP BEAM

Application filed August 20, 1928. Serial No. 300,825.

My invention relates to an improved warp beam and more particularly to a positive locking device for locking together the head and barrel portions of the warp beam to prevent relative rotation. When used on a high speed warper, such as a Barber-Colman warper, there is a tendency to relative rotation between the barrel and the head when the rapidly rotating beam is brought to a quick stop. This relative rotation is undesirable when there is a break in the yarn as it permits several yards of yarn to run off the creel before the broken yarn may be fixed.

It is an object of my invention to provide a simple, positive locking device for a warper beam head which is simple in structure, reliable in operation and economical of manufacture.

Another object of my invention is to provide a positive locking device for use on a warp beam which dispenses with the need of internal fastenings or screws or bolts on the inside of the barrel of the warp beam which sometimes work loose and wreck the beam.

A further object of my invention is to provide a warp beam head which is light and yet sufficiently strong to withstand the centrifugal force induced by rotation at very high speed.

Still another object of my invention is to provide a locking device for a warper beam which comprises lug portions on the head members which fit within notch portions on the extremities of the barrel member, the lug portions and the notch portions being so distanced from the axle as to effectively resist the tendency to relative rotation and simultaneously resist the tendency to break.

Other objects and advantages will appear from the following description taken in connection with the accompanying drawing.

I attain these objects and advantages by means of the constructions shown in the accompanying drawing, wherein

Figure 1 is a sectional view of the end of a warp beam showing the locking means on the head member fitting into the notches on the end of the barrel member. There is a further

showing in this figure of a split nut which fits into the wooden center for strengthening the same.

Figure 2 is an elevational view of the inner face of the head member.

Figure 3 is an elevational view of the outer face of the head member showing a nut lock device for preventing the turning of the axle nut.

Figure 4 is an end view of the barrel member showing the notches provided in the inner periphery of the lagging.

Figure 5 is an enlarged view of a disk member for attachment to a head member having peripheral lugs for insertion into the notches on the barrel member and having cored bosses for the insertion of tie bolts for securing the same to the head member.

Figure 6 is a cross sectional view of the disk member shown in Figure 5.

Figure 7 is a side elevational view of the disk member shown in Figure 5 showing the side reverse to that in Figure 5.

Similar numerals refer to similar parts throughout the several views of the drawing.

Referring to Figure 1 of the drawing, 1 denotes a head member, 2 the barrel member of a warp beam, a shaft or gudgeon 3 passes through the center of the head member and through the axial center of the barrel member 2. Mounted on the shaft 3 is the wooden center 4, being secured in place by a split nut 5 which provides a bearing surface for the wooden center against the shaft 3. Lag screws 6 are provided for positioning the wooden center. Each extremity of the barrel portion is provided with notches 7 (see Figure 4) which serve a purpose to be stated hereinafter. The head member shown, is a large disk of laminated wood secured together by a rim and is a well known construction, however, it is to be understood that any other type of wheel may be used and that the invention is equally applicable to wooden or metal beam heads.

Secured to the head member 1 by the bolts 8 and concentric therewith, is a disk member 9. The disk member, as shown in Figure 2, is fixedly secured to the head member by

means of the bolts 8. The disk member is provided on its periphery with several abutments or locks 10 which are adapted to fit within the notches 7 above mentioned. The locks 10 are wooden pieces which fit into notches formed in the periphery of the disk as shown in Figure 2 where one of the nuts is omitted to more clearly show the construction of the lock. The disk 9 is of such diameter as to be insertible into the counterbore 21 of the barrel member and to fit snugly therein. The head member is held in fixed engagement with the barrel member by means of the axle nut 11. In order to prevent the working loose of the axle nut 11, a locking device 12 is provided. As shown in Figure 3, this locking device consists of a strap member which has a hexagonal opening therein which is adapted to circumscribe the exterior of the nut and thereby prevent its turning. This strap member is placed on the head member after the nut is screwed on its maximum distance. The opening in the strap member may be varied to fit the contour of the nut. It is apparent that in order to remove the nut it is necessary to first remove the locking strap. This is of great importance in order to prevent the working loose of the head and barrel members.

Referring to Figures 5 and 6, there is there shown a metal disk member 15 which serves the same purpose as the disk 9 above referred to. The disk 15 is provided with cored bosses 16, the flange 17 and peripheral lugs 18. In position, the bosses are disposed between the disk and the head member and relieve the bolts of the strain incident to the starting torque. Reinforcing ribs 19 are provided for each of said lugs to strengthen the same. The disk may be made of cast-iron or any other suitable material. It may be placed on any wheel, the holding bolts passing through the openings 20 in the bosses 16, the lugs 18 fitting into the notches provided therefor in the ends of the barrel lagging.

As previously stated, with respect to the disk 9, the diameter of the disk 15 is such that the flange 17 fits within and snugly contacts the inner periphery of the counterbore 20 of the barrel.

The operation of the device is obvious from an inspection of the drawing and it will be appreciated that upon the sudden stoppage of the warp beam that the locking means shown will be sufficient to withstand any tendency to relative rotation between the head and barrel members. The distance of the locking means from the axial center of the barrel is such as to reduce the tendency to breaking or shearing of the locking elements.

It should be understood that although the locking means here described and illustrated are shown attached to a disk which in turn is attached to the head member, it would be

feasible to have the locking devices consist of individual members directly attached to the head member. Likewise the relation of projections and notches could be reversed so that the notches would be formed in the head member and the barrel end be provided with projections for insertion in said notches. The invention relates to a direct locking means between the end of the barrel and the head member and all constructions depending upon this feature are within the purview of this invention.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure or substitution of equivalents which utilize the principle of my invention, and fall within the purview of my invention and are within the spirit and scope of the following claims.

The invention having been set forth, what is claimed as new and useful is:

1. A warp beam having in combination, a barrel and a head, said barrel having a counterbore, a disk secured to said head and being adapted to fit within said counterbore, said barrel having notches at its ends, and means on said disk for coacting with said notches to lock said barrel and head against relative rotation.

2. A warp beam having in combination, a barrel member, head members, the extremities of said barrel member having notches formed therein, and means on said head members for insertion in said notches to prevent relative rotation of the head and barrel members.

3. In a warp beam, a head member, a barrel member having a counterbore, one of the faces of said head member contacting with said barrel member, said contacting face having disposed thereon means concentric with said head member, said means being adapted to fit within said counterbore, said barrel member being provided with notches at its counterbore and projections on said means for engaging said notches to prevent relative rotation of the head and barrel members.

4. In a warp beam, a head member, a barrel member having a counterbore, a disk member on said head member adapted to fit within said counterbore, said barrel member being provided with notches on the inner periphery of each end, and lug means on the periphery of said disk member for engaging said notches.

5. In combination with a warp beam comprising a barrel member and head members, a disk member secured to each of said head

members and being adapted to fit within the counterbore of said barrel member, said barrel member having notches on the inner periphery of each end, said disk member having 5 lugs on its periphery which are adapted to coact with the end of the barrel member to prevent relative rotation.

6. A warp beam having in combination, a barrel member and a head member, said barrel 10 having an edge portion contacting said head member, said edge portion having spaced notches therein and means on said head for insertion into said notches to directly lock said edge portion to said head member.

15 Signed at Fall River in the county of Bristol, State of Massachusetts, this tenth day of August, 1928.

JABEZ WILKINSON.
